UNITED STATES PATENT OFFICE.

ARTHUR H. GOLDFINGHAM, OF NEW YORK, N. Y., ASSIGNOR TO DE LA VERGNE MACHINE COMPANY, OF NEW YORK, N. Y., A CORPORATION OF NEW YORK.

INTERNAL-COMBUSTION ENGINE.

No. 877,500.

Specification of Letters Patent.

Patented Jan. 28, 1908.

Application filed November 14, 1906. Serial No. 343,328.

To all whom it may concern:

Be it known that I, ARTHUR H. GOLDFINGHAM, a subject of Great Britain, residing in the borough of Manhattan, city of New York, in the county of New York and State of New York, have invented certain new and useful Improvements in Internal-Combustion Engines, of which the following is a specification, reference being had therein to the accompanying drawings, forming a part thereof.

My invention relates broadly to internal combustion or explosion engines, and more particularly to oil engines adapted to use the heavier oils, such as kerosene or petroleum, or similar oils of a high specific gravity; and my invention relates yet more particularly to that type of the last named engines in which the oil is introduced into and vaporized in and the vapor ignited in a chamber separate from the working cylinder, but communicating freely therewith through a contracted passage or neck, air being admitted separately to the cylinder, and a combustible mixture being formed only when compression takes place and the air from the cylinder is thereby forced into the chamber. In this type of engine ignition takes place as a result of compression and of the heat of combustion retained by the walls of the chamber.

The objects of my invention, broadly stated, are economy, efficiency, convenience and reliability of operation.

More specifically stated, the principal object of my present invention is to secure more nearly perfect combustion. More complete combustion enables heavier oils to be employed as fuel than heretofore, and also results in increased economy, whatever kind of fuel is employed. Also, the deposit of carbonaceous material in the combustion chamber is reduced, whether heavier or lighter oils are used, so that cleaning is required much less frequently.

Other objects and advantages will herein-after appear.

Broadly considered, my invention includes means for introducing air in a novel manner into the combustion chamber, where it is mixed with the vapor prior to ignition, the quantity of air thus introduced being sufficient to secure the desired result of more complete combustion, and air also being admitted directly into the cylinder, and igni-

tion depending upon the compression of the 55 contents of the cylinder and the combustion chamber.

More specifically my invention comprises, the combination with a chamber such as above described, of a spraying nozzle opening into the combined vaporizing and combustion chamber, oil being supplied to the nozzle by a pump, and air under pressure being also supplied to the nozzle and effecting a better spraying of the oil and a dilution 65 of its vapor in the combined vaporizing and combustion chamber.

The particular embodiment of my invention illustrated will now be described by reference to the accompanying drawings, 70 after which I will point out my invention in claims.

Figure 1 is a plan view of an oil engine embodying the present invention, the cylinder, valve-chest and vaporizing chamber 75 being shown in horizontal section, and the engine being shown as coupled to an air compressor. Fig. 2 is a side elevation, on a slightly enlarged scale, of the head end of the engine. Fig. 3 is an end elevation, looking toward the head end of the engine, portions of the cylinder and valve-chest being broken away so as to show the air-inlet valve for the cylinder. Fig. 4 is a considerably enlarged longitudinal sectional 80 elevation of the nozzle employed for introducing oil and air into the vaporizing chamber. Fig. 5 is a section taken on the line 5—5 of Fig. 4 as viewed from the right, and shows both the oil and air-inlets for the 85 nozzle. Fig. 6 is a section taken on the line 6—6 of Fig. 4 as viewed from the right.

The drawings illustrate the type of engine known as the Hornsby-Akroyd oil engine and disclose one embodiment of my invention as incorporated in the construction of such engine. The engine has a working cylinder 11 and a combined vaporizer and combustion chamber 12 attached to the head end of the cylinder and opening freely 95 into the cylinder through a neck or contracted passage 13. The vaporizer is shown as provided with a projection 15 in which is formed a hand-hole through which the interior of the vaporizer may be cleaned 100 when necessary, this hand-hole being closed by a cover 14. The cylinder is provided with a working piston 16 and during the

suction stroke of this piston, the engine shown being of the four-cycle type, air is drawn into the cylinder through a port 17, air-inlet valve 18 and air suction pipe 19. 5 The air-inlet valve 18 is normally held upon its seat by a spring 20 and is held open during the suction stroke of the working piston by a lever 21 acted upon by a cam 22 carried by a cam-shaft 23 driven by the 10 engine crank shaft 24 in the usual manner. Also, during the suction stroke of the working piston, oil is introduced into the vaporizer 12, and in the present invention air is also introduced into the vaporizer during 15 the suction stroke of the piston 16. In the embodiment of the invention illustrated both the oil and air are introduced into the vaporizer through the fuel inlet consisting of a spraying nozzle, the delivery tube 32 20 of which passes obliquely through the wall of the vaporizer, oil being supplied to the spraying nozzle through a pipe 26 leading from an oil-pump 27, and the latter receives oil through an oil supply pipe 28. Air under 25 pressure is supplied to the spraying nozzle through a pipe 29 leading from an air container 30, which receives its supply from an air compressor 31, shown in this instance as coupled to and driven by the engine shaft 24. 30 It should be understood that the compressed air that is introduced into the vaporizing chamber 12 may come from any convenient source, such source being either dependent upon the engine, as shown, or 35 entirely independent thereof.

The spraying nozzle, through which, in the embodiment of the invention illustrated, both oil and air are introduced into the vaporizer 12, includes the delivery tube 32 40 having a spray or delivery opening 33 controlled by a needle-valve 34. The valve 34 has a stem 35 passing back through the delivery tube 32 and then through a packing gland 36, the outer end of the valve-stem 45 having a center-bearing in a spring-engaging thimble 37. To normally hold the valve 34 closed a coiled expansion spring 38 is provided and acts between the thimble 37 and a second thimble 39, the latter acting as an 50 abutment. The thimble 39 is held in place and the spring 38 rendered adjustable as to its tension by a bearing screw 40, supported in a cap or end cover 41 shown as secured to a casing 42 by studs 43, the casing 42 in turn 55 being supported upon the sleeve 32 by means of bolts 44 passing therethrough and through lugs 45 on the delivery tube 32.

For thoroughly mixing the oil and the air, thus producing a better spraying effect, a 60 tortuous passage is provided for the air and oil within the delivery tube 32. The tortuous passage is formed by a core 46 fitting within the tube 32 and provided with annular grooves 47 which are connected with 65 each other alternately on opposite sides by

notches 48. The core 46 is supported between the end of the tube 32 adjacent to the delivery opening 33 and the inner end of the cup or sleeve of the packing gland 36, an outlet space being provided between the end 70 of the delivery tube 32 and the end of the core 46 by spacing legs 49 carried by the core.

Oil enters the nozzle through an oil-inlet 50 to which is connected the oil-pipe 26. Compressed air enters the nozzle through an 75 air inlet 51 to which is connected the air-pipe 29. To guard against any possibility of oil, or the products of combustion at the time of explosion, escaping through the air-inlet 51, a back-pressure or check valve 52 is provided 80 in the air-inlet, this back-pressure valve 52 being normally held upon its seat by a spring 53 acting upon its stem 43. The valve stem 54 is shown as protected by a screw cover-cap 55.

When the nozzle-controlling valve 34 is closed, as shown in Fig. 4, it is evident that neither oil from the pipe 26 nor air from the pipe 29 can pass into the vaporizer 12. It is also evident that, by reason of the free 90 communication from the receiver 30 to the air-inlet 51, compressed air from the receiver 30 will be injected into the vaporizer whenever and so long as the valve 34 is open, provided the pressure within the vaporizer is 95 less than that within the air-receiver 30. It is further evident that if the oil-pump be operated while the valve 34 is open, oil will be sprayed into the vaporizer, but will only be thus sprayed while the pump is being 100 operated.

In the embodiment of the invention illustrated, air and oil are injected into the vaporizer only during the suction stroke of the working piston 16, the air being injected 105 throughout such suction stroke and the oil only during a portion thereof, the first portion of such stroke. Therefore, means are provided for holding the nozzle-controlling valve 34 open throughout the suction stroke 110 of the working piston 16, and also for operating the oil-pump at the beginning of such stroke. Such means comprise a bell-crank lever 56 pivoted in the casing 42 on a pin 57 and having a forked arm 58 engaging with a 115 bearing plate or washer 59 upon the valve stem 35. The plate 59 is adjustable by nuts 60 on the valve stem to vary the extent to which the valve 34 is opened. The lever 56 is actuated by a pin 61 guided in a sleeve 62 120 forming an extension from the delivery tube 32. The pin 61 is acted upon by a lever 63 shown as pivoted at 64 upon a bracket 65 extended from the cylinder 11. The lever 63 is shown as actuated by a cam 66 carried 125 by the cam-shaft 23. The bracket 65 forms bearings at 67 for the shaft 23, and also is shown as having a forked extension 68 forming a support for the casing 42 of the spraying nozzle.

The lever 21 for actuating the air-inlet valve 18, for admitting air to the cylinder 11, is shown as fulcrumed upon a pivot pin 69 supported by a bearing bracket 70, and 5 carries a tappet-screw 71 for engaging the stem 72 of the valve 18. The cam-shaft 23 carries a third cam 73, for actuating an exhaust-valve 74, through the intermediary of a lever 75 and tappet 76 (see Fig. 2) in a 10 similar manner to the actuation of the air-inlet valve 18 by the lever 21. The exhaust-valve 74 and its actuating means have nothing directly to do with the present invention, but are shown and here referred 15 to merely for the sake of completeness. The nozzle-controlling lever 63, the exhaust-valve-actuating lever 75 and the air-inlet valve-actuating lever 21, for admitting air to the cylinder, are shown as provided, 20 respectively, with antifriction rollers 77, 78 and 79, to be engaged by the respective cams 68, 73 and 67. The cams are relatively disposed around the shaft 23 so as to actuate the corresponding levers at proper times. 25 The cylinder air-inlet valve 18 and the vaporizer nozzle-controlling valve 34 are both simultaneously opened and held open substantially throughout the suction stroke of the working piston 11. The relative 30 positions of the various parts when these two valves are open are illustrated in Figs. 2 and 3, these views corresponding to about the middle of the suction stroke, as may be readily understood by the middle position 35 of the cam 22 upon the roller 79 of the lever 21 which actuates the cylinder air-inlet valve 18. This is best seen in Fig. 3. The simultaneous operation of the nozzle-controlling valve 34, which admits air under 40 pressure to the vaporizer, is also made apparent by the middle position of the cam 66 upon roller 77 of the lever 63. Whenever the valve 34 is held open air will freely flow under pressure from the air-receiver 30 and 45 be injected into the vaporizer 12 through the opening 33, at the tip of the nozzle delivery-tube 32; and when the valve 18 is held open, atmospheric air will be drawn into the cylinder 16 through the pipe 19 and 50 port 17.

The oil pump 27 is operated simultaneously with the opening of the two inlet valves 18 and 34. The mechanism for actuating the oil-pump at the proper time, 55 comprises in combination with its plunger rod 80, a bearing plate 81 carried by the air-valve lever 21 and bearing upon the end of the plunger rod 80 to give it a working stroke into the oil-pump cylinder 27. The 60 plunger 80 is shown as operated in the opposite or return direction by a compression spring 81' acting on an extension 82 of the plunger 80 and guided in an extension 83 from the bracket 65, simultaneous movement 65 of the plunger 80 and lever 21 being

assured by reason of an offset 84 upon the extension 82 and engaging the upper face of the lever 21.

It is apparent that the plunger 80 is given its working stroke simultaneously with the opening of the inlet valves 18 and 34, such movement being imparted directly by the lever 21 as it opens the valve 18. As the cylinder-inlet valve 18 is opened at the beginning of the suction stroke of the engine, 70 the oil-pump is therefore operated to deliver oil during the first part of such stroke of the engine, the oil being forced into the oil-inlet 50 of the spraying nozzle. As the nozzle-controlling valve 34 is at this time open, the 80 oil will be sprayed into the vaporizer 12 by the combined action of the oil-pump and of the compressed air entering through the air-inlet 51 and air-check-valve 52. The spray of oil will be projected against the heated 85 walls of the vaporizer and the oil will thus be vaporized, the air that enters through the nozzle being mixed with this vapor. It is evident that the oil-pump will cease to deliver oil to the spraying nozzle as soon as the 90 lever 21 comes to rest, corresponding to the most widely open position of the air inlet valve 18. It is further evident that, as the nozzle-controlling valve 34 will continue to remain open throughout the suction stroke 95 of the engine, as before explained, air will continue to be injected into the vaporizer after the spray of oil has ceased. This air will mix with and further dilute the oil vapor contained within the vaporizer. 100

It should be understood that the air introduced into the vaporizer is not sufficient in quantity to produce a combustible mixture when mixed with the oil vapor, thus obviating the danger of premature ignition. 105 A combustible mixture is formed only when the air in the cylinder 11, which has entered through the port 17 and valve 18, is forced into the vaporizer 12 by the compression stroke of the piston 16. Ignition then takes 110 place from the heat of the walls of the vaporizer supplemented by the heat of compression. Heat may be applied to the outside of the vaporizer for starting the engine, after which the heat of combustion therein will be 115 amply sufficient. The combustible mixture is improved by the air which has been introduced directly into the vaporizer and thoroughly mixed with the vapor, so that combustion is rendered more complete. Also, 120 the compressed air thus introduced directly into the vaporizer has a cooling effect upon the vaporizer which is of advantage, as the vaporizers tend to become too hot.

It is obvious that various modifications 125 may be made in the construction shown and above particularly described within the principle and scope of my invention.

I claim:

1. In an internal combustion engine, the 130

- combination of a working cylinder, a piston therein, an air-inlet for the cylinder, a vaporizer communicating directly with the cylinder by a contracted passage always open, means for introducing fuel into the vaporizer during the first part of the suction stroke of the piston, and means for introducing air into the vaporizer substantially throughout the suction stroke of the piston.
2. In an internal combustion engine, the combination of a working cylinder, a piston therein, an air-inlet for the cylinder, a vaporizer communicating directly with the cylinder by a contracted passage always open, and means for introducing a mixture of fuel and air into the vaporizer during the first part of the suction stroke of the piston and for continuing the introduction of air substantially throughout the suction stroke.
3. In an internal combustion engine, the combination of a working cylinder, a piston in the cylinder, an air-inlet valve for the cylinder, means operated by a moving part of the engine for holding the valve open during the suction stroke of the piston, a vaporizer communicating directly with the cylinder, a combined fuel and air inlet valve for the vaporizer, and means operated by a moving part of the engine for holding the last named valve open during substantially the whole suction stroke of the piston.
4. In an internal combustion engine, the combination of a working cylinder, a piston in the cylinder, an air-inlet valve for the cylinder, means operated by a moving part of the engine for holding the valve open during the suction stroke of the piston, a vaporizer communicating directly with the cylinder by a contracted passage always open, a spraying nozzle opening into the vaporizer, means for supplying fuel to the nozzle, means for supplying air under pressure to the nozzle, a valve controlling the nozzle, and means operated by a moving part of the engine for holding the last named valve open during the suction stroke of the piston.
5. In an internal combustion engine, the combination of a working cylinder, a piston in the cylinder, an air-inlet valve for the cylinder, means operated by a moving part of the engine for holding the valve open during the suction stroke of the piston, a vaporizer communicating directly with the cylinder by a contracted passage always open, a spraying nozzle opening into the vaporizer, means for supplying fuel to the nozzle during a portion of the suction stroke of the piston, means for supplying air under continuous pressure to the nozzle, a valve controlling the nozzle, and means operated by a moving part of the engine for holding the last named valve open during the suction stroke of the piston.
6. In an internal combustion engine, the combination of a working cylinder, a piston 65 in the cylinder, an air-inlet valve for the cylinder, means operated by a moving part of the engine for holding the valve open substantially throughout the suction stroke of the piston, a vaporizer communicating directly with the cylinder by a contracted passage always open, a spraying nozzle opening into the vaporizer, a valve controlling the nozzle, means operated by a moving part of the engine for holding the last named valve 70 open substantially throughout the suction stroke of the piston, a pump for forcing fuel into and through the nozzle during a portion of the suction stroke of the engine piston, a fuel conduit from the pump to the nozzle, a source of compressed air, an air conduit from said source to the nozzle, and a back-pressure valve for the air conduit.
7. In an internal combustion engine, the combination of a working cylinder, a piston 85 in the cylinder, an air-inlet valve for the cylinder, means operated by a moving part of the engine for holding the valve open substantially throughout the suction stroke of the piston, a vaporizer communicating directly with the cylinder by a contracted passage always open, a spraying nozzle opening into the vaporizer and having a fuel inlet and an air inlet, an outwardly opening valve in the nozzle controlling the outlet of the 90 same into the chamber, a spring holding the valve on its seat, means operated by a moving part of the engine for holding the last named valve open substantially throughout the suction stroke of the piston, a pump for 100 supplying fuel to the fuel inlet of the nozzle during a portion of the suction stroke of the engine piston, a source of compressed air communicating with the air inlet of the nozzle, and a back-pressure valve in the air inlet 105 of the nozzle.
8. In an internal combustion engine, the combination of a working cylinder, a piston in the cylinder, an air-inlet valve for the cylinder, means operated by a moving part 110 of the engine for holding the valve open during the suction stroke of the piston, a vaporizer communicating directly with the cylinder by a contracted passage always open, a spraying nozzle opening into the vaporizer, means for supplying fuel to the nozzle, and means for supplying air under pressure to the nozzle, the nozzle having a tortuous passage therein, whereby the oil and the air are 115 intimately intermixed in passing through the 120 nozzle.
